UNITED STATES PATENT OFFICE

152,478

DESIGN FOR A FISH MOUTH OPENER OR SIMILAR ARTICLE

Francis H. Hutchinson, Denver, and Cyral T. Walsh, Larimer County, Colo.

Application July 30, 1947, Serial No. 140,624

Term of patent 7 years

(Cl. D11—1)

To all whom it may concern:

Be it known that we, Francis H. Hutchinson and Cyral T. Walsh, citizens of the United States, residing respectively in the city and county of Denver and Larimer County, both in the State of Colorado, have invented a new, original, and ornamental Design for Fish Mouth Opener or Similar Article, of which the following is a specification, reference being had to the accompanying drawing, forming a part thereof.

We claim:

The ornamental design for a fish mouth opener or similar article, as shown.

FRANCIS W. HUTCHINSON.
CYRAL T. WALSH.
